 Brian James Brewer

(57) **CLAIM**

We claim the ornamental design for a lighting assembly, as shown and described.

DESCRIPTION

FIG. 1 is a bottom perspective view of a lighting assembly of the present disclosure;

FIG. 2 is a bottom perspective view of the lighting assembly of FIG. 1;

FIG. 3 is a bottom perspective view of the lighting assembly of FIG. 1; and,

FIG. 4 is a bottom plan view of the lighting assembly of FIG. 1.

The broken lines immediately adjacent the shaded areas represent the bounds of the claimed design while all other broken lines are directed to portions of the lighting assembly and form no part of the claimed design.

1 Claim, 4 Drawing Sheets
